I. M. JONES

VALVE CORE SEATING AND REMOVING MACHINE

Filed Jan. 15, 1923

FIG. 1

FIG. 2

INVENTOR

Ithmer M. Jones

By Ralph Taenish
ATTORNEY

Patented May 12, 1925.

1,537,534

UNITED STATES PATENT OFFICE.

ITHMER M. JONES, OF TAYLORVILLE, ILLINOIS, ASSIGNOR OF ONE-HALF TO SAMUEL SCUDDER, OF TAYLORVILLE, ILLINOIS.

VALVE-CORE SEATING AND REMOVING MACHINE.

Application filed January 15, 1923. Serial No. 612,872.

To all whom it may concern:

Be it known that I, ITHMER M. JONES, a citizen of the United States, residing at Taylorville, county of Christian, and State 5 of Illinois, have invented a certain new and useful Improvement in Valve-Core Seating and Removing Machines, of which the following is a specification, reference being had to the accompanying drawing, forming

10 a part thereof.

This invention relates to a certain new and useful improvement in valve-core seating and removing machines.

The valve proper of an inflatable tire- 15 tube or the like usually includes an internally threaded stem or casing and a valve-plunger or core, the latter being thread-seated for operation within the stem or casing.

20 My present invention has for its chief object the provision of a relatively simple, readily operated, and efficient machine, whereby the cores or plungers of valves of the type mentioned may be seated in or re- 25 moved from the valve-stems with convenience, facility, and quickness.

With the above and other objects in view, my invention resides in the novel features of form, construction, arrangement, and 30 combination of parts hereinafter described and afterwards pointed out in the claims.

In the accompanying drawing,

Figure 1 is a side elevational view of a valve-core seating and removing machine 35 embodying my invention; and

Figure 2 is a front view, partly in vertical section, of the machine.

Referring now more in detail and by reference characters to the said drawing, which 40 illustrates a preferred embodiment of my invention, the machine includes a standard or body 1 provided at its lower end with a base-plate 2 adapted for rigid attachment to a table or other place of support. At 45 its upper end, body or standard 1 is formed preferably integrally with a lateral arm 3 provided at its free end with spaced so-called bearing-fingers 4 and 5.

50 Mounted for rotation upon finger 4, is a relatively large bevel-gear 6 provided with an operating handle or crank 7 and meshing with a smaller bevel-gear 8 fixed upon the upper end of a vertically disposed stub-shaft 9 arranged for rotation in bearing-finger 5, as best seen in Figure 2. Carried for ro-

60 tation by shaft 9 at its lower-end, is a depending core-engaging and manipulating or actuating tool or bit 10. Suitably attached at one end, as at 11, to standard-arm 3, is an angular-member or bracket 12 carrying at its outer end a substantially U-shaped member 13 embracing the working end of tool or bit 10, as also best seen in Figure 2, for purposes shortly appearing.

65 Formed upon the base 2 of standard 1 in proper vertical alignment with the tool or bit 10, is a tubular-support 14 for a suitably elongated vertically disposed tubular spring-housing 15 preferably permanently closed at its lower end, as at 16. Disposed within 70 housing 15, is a coiled expansion spring 17, and yieldingly supported by spring 17 and adapted for lengthwise movement relatively to and within housing 15, is the post or pedestal 18 of a preferably circular table 19, 75 a cap-plate 20 fastened to housing 15 and engaging post 18, as seen in Figure 2, retaining the post 18 and its supported plate 19 in operative relation to the supporting-spring 17 and its housing 15.

80 In use or operation, the inflatable tube is placed upon table 19, as indicated in dotted lines in Figure 2, and its carried stem disposed within the chamber or cavity of member 13, as shown, in operative vertical alignment with tool or bit 10, table 19 conveniently yielding to suitably accommodate and permit proper placement of the tube and stem. In seating a core or plunger within the stem, the core is now placed 85 suitably within the stem and engaged by the bit 10, the member 13 facilitating proper co-operative placement of the stem and core. On rotary actuation of the bit 10 by the crank 7 in the proper direction, the core, 90 in turn, will be rotarily actuated and thereby thread-seated for operation within the stem. On the other hand, in the removal of a core from a stem, the tool 10 being 95 suitably engaged with the core and reversely actuated, the core will be readily unseated for removal.

100 My new machine is simple in form and construction, may be cheaply manufactured, and is exceedingly efficient in the performance of its intended functions.

I am aware that minor changes in the form, construction, arrangement, and combination of the several parts of the machine 105 may be made and substituted for those here- 110

in shown and described without departing from the nature and principle of my invention.

Having thus described my invention, 5 what I claim and desire to secure by Letters Patent is:

1. A machine for thread seating in and removing cores from valve stems including, in combination, a standard, a table upon 10 the standard for supporting the tube and stem, a tool mounted upon the standard for rotary movement in a vertically stationary plane above the table for actuating the core to be thread-seated in or removed 15 from the stem, means upon the standard for rotary actuating the tool, and spring means yieldingly urging said table toward said tool.

2. A machine for thread seating in and 20 removing cores from valve stems including, in combination, a standard, a yielding table upon the standard for supporting the tube and stem, a tool mounted upon the standard for rotary movement in a vertically stationary plane above the table for actuating 25 the core to be thread-seated in or removed

from the stem, means upon the standard for 30 rotarily actuating the tool, and a rigid member fixed upon the standard and embracing the tool for facilitating co-operative placement between the stem and core.

3. A machine for thread seating in and removing cores from valve stems including, in combination, a standard, a table mounted 35 for yielding movement upon the standard for supporting the tube and stem, an arm projecting laterally from the standard, a vertically disposed shaft mounted upon the arm for rotary movement in a vertically stationary plane above the table, a tool carried by said shaft for rotarily actuating the core to be thread-seated in or removed from the stem, means upon the standard comprising a gear fixed upon the shaft for rotarily actuating the tool, and a rigid substantially 40 U-shaped member fixed upon the standard to embrace the tool for facilitating the co-operative placement of the stem and core.

In testimony whereof, I have signed my name to this specification.

ITHMER M. JONES.
